UNITED STATES PATENT OFFICE.

CHARLES HUNGERFORD, OF SOLDIER, KANSAS.

DITCHING-MACHINE.

1,171,203.

Specification of Letters Patent.

Patented Feb. 8, 1916.

Application filed March 31, 1915. Serial No. 18,264.

To all whom it may concern:

Be it known that I, CHARLES HUNGERFORD, a citizen of the United States, and a resident of Soldier, in the county of Jackson and State of Kansas, have invented a new and Improved Ditching-Machine, of which the following is a full, clear, and exact description.

This invention relates to machines for ditching or grading, and has particular reference to means of this character adapted to be drawn ordinarily by horses or a traction engine and designed for various specific purposes.

15 Among the objects of the invention is to provide a machine of the general character indicated, including a frame, one portion of which constitutes a longitudinal guide bar or runner and that part of the frame extending laterally therefrom is adapted to be supported at various elevations by a roller or wheel.

One of the purposes of the invention is to open out furrows or ditches for draining or 25 tiling purposes.

Another purpose of the invention is to attach auxiliary cutters or scrapers to the main frame runner member at any suitable angle with respect to the horizontal for the 30 purpose of scalping off one or both of the shoulders formed by the ditching bit or colter and for scraping the loose dirt laterally toward the center of the road bed in connection with road machines.

35 The foregoing and other objects of the invention will hereinafter be more fully described and claimed and illustrated in the drawings forming a part of this specification in which like characters of reference 40 indicate corresponding parts in all the views, and in which—

Figure 1 is a perspective view of a preferred embodiment of the invention; Fig. 2 is a plan view of the main parts of the 45 same; and Fig. 3 is a side elevation of the front part of the same, parts being in section on the line 3—3 of Fig. 2.

The several parts of this device may be made of any suitable materials, and the 50 relative sizes and proportions, as well as the general design of the mechanism, may be varied to a considerable extent without de-

parting from the spirit of the invention hereinafter more fully described and claimed.

Referring more particularly to the drawings I show at 10 a substantially flat longitudinally arranged bar or plate termed hereinafter the runner, and which constitutes the main element of the frame of the machine. At 11 is a horizontally extended frame member of any suitable length determining substantially the width of the machine, and the outer end of this transverse member is connected by a diagonal brace 12 65 with the rear portion of the runner.

13 indicates a second longitudinal member parallel to the runner and of approximately the same length which constitutes with the runner a support for a draft connection 14 70 having a series of holes 14' therein. A draw bar 15 is pivotally connected at 15^a to the main cross bar 11 and adjustably connected in one of the holes 14' for determining the forward inclination of the draw bar. 75

At 16 I show a bar rigidly connected to the runner and extending forwardly therefrom forming a support for a cutter head 17 pivoted to the bar 16 by means of a pivot 18. The cutter head comprises a colter 19 80 extending downwardly and rearwardly from the pivot 18 and having secured thereto a ditch forming device 20. The drawing indicates one form of these ditch forming devices and opposite each other at 85 the front end of the runner. The ditch forming device comprises a plate 20^a and an angularly disposed blade 20^b. The plate 20^a is comparatively thin and is secured flatly against the colter 19 by bolts or 90 rivets 21, the forward edge of the plate conforming to the adjacent edge of the colter. The blade 20^b extends laterally in a plane substantially perpendicular to the plane of 95 the plate and inclined upwardly and rearwardly from the front and cutting edge of the colter. The front inclined edge of the colter and cutter head constitutes a form of ditch opener, and the lower and front edges of the blades 20^b constitute cutters defining the bottom of the ditch or furrow.

The cutter head, with the limitations stated below is pivoted to swing in a substantially vertical plane around the pivot 18,

2 but any suitable devices may be used to positively control such movements of the cutter head. The controlling means herein shown include a lever 22 pivoted at 18 and extending thence rearwardly in reach of the operator seated upon the machine at 23. A link 24 is pivoted at 25 to the lever and has connection through a pin 26 and slot 27 with the cutter head allowing a certain amount 10 of independent movement between the link and the cutter head. However, when the lever is lifted far enough, the pin 26 will lift the cutter head. At 28 I show a wedge connected pivotally at 29 to the lever and 15 adapted to be forced thereby downwardly snugly between the rear beveled end of the colter 19 and the extreme front end of the runner 10, whereby, as shown in Fig. 3, the cutter head is locked in a downward position 20 and held snugly as though abutting against said end of the runner.

At 30 I show a side cutter comprising a vertical side plate 30^a and a flat blade 30^b at substantially a right angle and with its lower or cutting edge 30^c inclined at an oblique angle with respect to the horizontal and with the plane of the blade inclined upwardly with respect to the bottom of the runner. This side cutter blade 30^b serves 25 to scalp off the angular shoulder formed by the cutter head on one side of the runner so as to loosen the dirt and allow it to be scraped laterally to a considerable distance by means of a drag blade 31. This drag 30 blade is connected at one end to the runner at 32 and extends laterally and rearwardly and at any desired elevation with respect 35 to the horizontal.

33 indicates a brace extending laterally 40 between the middle portion of the drag blade and the rear end of the runner, and at 34 I show an arch support or brace connecting the same with the rear end of the frame member 13. When used as a road machine, 45 this drag blade serves to scrape or throw the dirt loosened by the cutter head 17 and the side cutter 30 over in a ridge-like manner toward the center of the road bed.

The side supporting wheel 35 is mounted 50 upon a support 36 journaled in a bracket or bearing 37 and held at any desired elevation by means of a drag rod 38. By this means any desired tilt laterally may be given to the runner and thereby the active edges 55 of the side cutter and drag blade may be variably inclined with respect to the horizontal.

I claim:

1. In a machine of the character set forth, 60 the combination of a main longitudinal frame member constituting a runner, a cutter head pivoted to and movable vertically adjacent the front end of the runner, means to lock the cutter head in definite cutting position with respect to the end of the runner,

devices connected to the rear portion of the runner and extending laterally therefrom at an angle to act upon the soil loosened by the cutter head, and draft connections for the machine.

70

2. In a machine of the class set forth, the combination of a main longitudinal frame member constituting a runner, means extending laterally from the runner to determine its relation to a vertical longitudinal 75 plane of action, a cutter head pivotally connected to the front end of the runner and movable in a vertical plane with respect thereto, and means to limit the upward movement of the cutter head and thereby 80 positively fix the depth of its cutting action, said cutter head having cutting blades extending laterally from both sides of the runner.

3. In a machine of the character set forth, 85 the combination of a longitudinal frame member constituting a runner, a bell crank axle journaled in the outer end of the frame devices, a wheel mounted upon said axle, a cutter head connected to the front end of 90 the runner, means to regulate the depth of cut thereof, and rigid cutting devices secured to one side of the runner and acting laterally therefrom on the same side as said wheel, the effective inclination of the latter 95 mentioned cutting devices being determined by the vertical adjustment of said frame through said wheel and axle.

4. In a machine of the character set forth, 100 the combination of a longitudinal frame member constituting a runner, supporting devices extending laterally from one side of the runner to determine the position thereof with respect to the longitudinal vertical 105 plane, a cutter head comprising a rib pivoted to the runner, said cutter head also including a pair of cutting blades secured rigidly to the rib on opposite sides thereof and also upon opposite sides of the runner, said blades having cutting edges substantially perpendicular to the plane of the runner and the main portions of the cutting blades lying in the same plane and extending upwardly and rearwardly from said edges, and means to determine the cutting 110 depth of the cutting head.

5. In a machine of the character set forth, 115 the combination of a runner constituting a main frame member lying in a longitudinal and substantially vertical plane, a bar connected to the runner and extending forwardly therefrom, a cutter head comprising a colter pivoted to the front end of the bar and extending thence downwardly and rearwardly in substantially the plane of the 120 frame member, a cutting blade secured to one side of the colter and extending rearwardly along the front end of the frame member, said cutting blade having a cutting edge substantially perpendicular to the 130

plane of the frame member, the blade extending thence upwardly from said edge at an inclination, and means to positively regulate the cutting depth of the cutter head, said last mentioned means comprising a lever, a wedge pivoted at one end to the lever and having its other end movable downwardly between the colter and the front end of the frame member, and a link

connected to the lever and having loose pin 10 and slot connection with the cutter head.

In testimony whereof I have signed my name to this specification in the presence of two subscribing witnesses.

CHARLES HUNGERFORD.
